UNITED STATES PATENT OFFICE.

CLARENCE S. STEWARD, OF CHATTANOOGA, TENNESSEE.

ELECTRIC OVEN.

1,087,200.

Specification of Letters Patent. Patented Feb. 17, 1914.

Application filed November 12, 1913. Serial No. 800,629.

To all whom it may concern:

Be it known that I, CLARENCE S. STEWARD, a citizen of the United States, residing at Chattanooga, in the county of Hamilton and 5 State of Tennessee, have invented certain new and useful Improvements in Electric Ovens; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 This invention relates to certain new and useful improvements in that class of electric cooking ovens in which heating plates or units are provided and it has for its object the provision of an oven of this character in which provision is had whereby articles contained within the oven can be subjected to a dry heat or cooked within a moist atmosphere as may be desired.

20 The invention has for a further object the provision of an electrically heated oven in which the walls of the chamber are imperforate and in which heating units are provided at the top and bottom of the chamber 25 so that heat may be imparted to the oven from either the top or bottom or both top and bottom as desired.

A further object of the invention resides 30 in the provision of valve-controlled connection between the upper portion of the oven and the outer air at a point slightly above the bottom of the oven.

The objects and advantages derived from 35 these features of construction will herein- 40 after more fully appear.

To these ends and to such others as the invention may pertain, the same consists in the novel construction of the oven and in the peculiar arrangement, combination and 45 adaptation of parts, all as will be more fully hereinafter described, shown in the accompanying drawings and then specifically defined in the appended claims.

The invention is clearly illustrated in the 50 accompanying drawings, which, with the letters of reference marked thereon, form a part of this specification and in which:—

Figure 1 is a horizontal section taken through an oven embodying my invention, 55 and Fig. 2 is a central vertical section of the same.

Reference now being had to the details of the drawings by numeral, 1 represents a casing forming the outer portion of the oven. This casing is provided with outer and inner walls 2 and 3 respectively, the intervening space between the said walls being filled with a mineral wool or other suitable non-conducting material. The interior of the chamber is provided at its top and bottom 60 with electric heat units 4 and 5 respectively. These units may be of any approved construction which may be found adapted to the purpose. In the drawings, however, I have shown a form of heater which consists of a 65 plate or body portion of steatite or soap-stone, the resistance wires being carried within horizontally disposed chambers formed in the body of the unit, the said chambers communicating with the face of the unit through contracted slots, the units being electrically connected by means of 70 switches 6 and 7.

The oven is provided at opposite sides at 75 points adjacent to the top of the oven with tubes 8, which tubes extend downwardly between the side walls of the oven and open at their lower ends into the outer air at the bottom of the oven, the outlets 9 being provided with operating valves 10 whereby 80 communication with the interior of the oven can be regulated. The front of the oven is provided with a tightly closing transparent door 11 through which access is had to the interior of the chamber. The inner faces of 85 the opposite side walls of the chamber are provided with metallic brackets 12, 12 which are designed to support at any desired height slotted metallic shelves. The oven is 90 designed to be provided with suitable supports, such as legs 13, shown in the drawings.

It will be noted that the valve-controlled 95 outlets of the tubes leading from the upper portion of the oven downwardly through the side walls have their exits at the bottom of the oven. By this arrangement, it is possible to obtain the results of wet or steam cooking or of dry cooking accordingly as to whether the valves or vents are opened or closed. When it is desired to cook by the dry process, 100 the valve-controlled outlets are opened and the steam resulting from the baking or other cooking within the oven is expelled through the valve-controlled outlets of the tubes. When, upon the other hand, it is desired to 105 cook by the wet process, it is simply necessary to close the tubes thereby confining the 110

moisture within the closed interior of the oven.

In the use of the oven in certain lines of cooking, such for instance as the roasting of meat, it is quite essential that the roast should be so cooked as to preserve in a great measure the moisture which is contained within the meat and this, it will be noted, can be readily accomplished by the closing 5 of the valves at the outlet tubes, thus confining the steam thrown off by the meat during the cooking process and maintaining the moisture within the oven. Upon the other hand, if the oven is used for baking purposes, it is essential that the interior of the oven should be as free as possible from moisture which could be accomplished by the opening of the outlet valves.

The placing of heat units at both the top 20 and bottom of the oven, the units being so disposed and electrically connected as to render it possible to use the units either singly or in unison, will be found decidedly 25 advantageous in baking, as the heat being radiated from both top and bottom simultaneously serves to permit an even, uniform browning of both bottom and top surfaces of the loaf. It will be noted that, if, upon looking through the transparent door of the 30 oven, it should at any time be found that more heat would be required either at the top or bottom of the loaf in order to produce the most effectual browning of the loaf, this can be readily accomplished by shutting off 35 the current from either the top or bottom heat unit as may be necessary.

Having thus described my invention, what I claim to be new and desire to secure by Letters Patent is:—

1. An electric oven comprising a chamber

provided with double side walls having the intervening space between the walls packed with suitable nonconducting material, a heat unit inclosed within the chamber, valve-controlled outlet tubes extending from openings provided at the tops of the side walls and having their outlet ends in the lower portion of the oven, substantially as shown and described.

2. An electric oven of the character described, the same comprising a chamber, the walls of which are packed with mineral wool or other nonconducting material, heat units disposed within the oven at the top and bottom thereof, valve-controlled tubes communicating at their upper ends with the upper portion of the oven and their lower ends at the bottom of the oven being provided with suitable check valves, substantially as shown and described.

3. The herein described electric oven, the same comprising a chamber, the side walls of which are packed with nonconducting material, the side walls upon opposite sides of the oven being provided with tubes communicating at their upper ends with the interior of the upper portion of the oven and at their lower ends being provided with valve-controlled outlets, independent heating units disposed at the top and bottom of the oven, and a transparent door through which the interior of the oven can at all times be seen, substantially as shown and described.

In testimony whereof I hereunto affix my signature in presence of two witnesses.

CLARENCE S. STEWARD.
